United States Patent

Des. 240,524
Patented July 13, 1976

240,524

BALL-POINT PEN

Alain Carre, Paris, France, assignor to
Waterman, S.A., Paris, France

Filed June 19, 1974, Ser. No. 480,834

Term of patent 14 years

Int. Cl. D19—06

U.S. Cl. D19—45

FIG. 1

FIG. 2

FIG. 3

FIG. 1 is a perspective view of a ball-point pen showing my new design;

FIG. 2 is a front elevational view thereof; and

FIG. 3 is a right side elevational view with the writing tip shown in an extended position.

I claim:

The ornamental design for a ball-point pen, as shown and described.
